UNITED STATES PATENT OFFICE.

WILLIAM L. PARMELEE, OF ANSONIA, CONNECTICUT.

AUGER.

SPECIFICATION forming part of Letters Patent No. 242,362, dated May 31, 1881.

Application filed March 31, 1881. (No model.)

To all whom it may concern:

Be it known that I, W. L. PARMELEE, a citizen of the United States, residing at Ansonia, in the county of New Haven and State of Connecticut, have invented certain new and useful 5 Improvements in Augers; and I do hereby declare the following to be a full, clear, and exact description of the invention, such as will enable others skilled in the art to which it applies to make and use the same, reference 10 being had to the accompanying drawings, and to the letters or figures of reference marked thereon, which form a part of this specification.

15 My invention relates to augers for boring purposes; and the novelty consists in the construction and adaptation of the same, as will be more fully hereinafter set forth, and specifically pointed out in the claim.

20 The object of the invention is to produce an auger which will hold itself to the cut and avoid the splitting or breaking upon the back of the board, timber, or the like, and this object I accomplish by means of the device shown, and herein described.

25 In the ordinary and well-known auger great difficulty is experienced at the last end of the auger-hole by the loss of holding-gripe, and the auger must either be forced through the 30 material, leaving a rough and uncouth exit-aperture, or the plank be reversed and the screw entered in the hole left by the operation from the opposite side.

35 In carrying out the invention I employ an ordinary auger, and affix the holding-screw, of gimlet form, in the center thereof. The duplex lips at the cutting end are so inclined inwardly that the screw will hold tenaciously until the cutting portion has entirely separated 40 the part described by the area or sweep of the auger. Each radial lip is provided with a cutting-spur, and the incline is such that the spur will be sufficiently in advance of the larger diameter or holding portion of the screw to insure the separation of the longitudinal fibers 45 of the wood, while the screw exerts its proper influence.

The invention is fully illustrated in the accompanying drawings, which form a part of this specification, and in which—

50 Figure 1 is a longitudinal elevation; Fig. 2, an enlarged view from another point of observation, and Fig. 3 an end detail view.

55 Referring to the drawings, in which similar letters of reference indicate like parts in all the figures, A represents the twisted body of the auger, and a the rectangular portion, as shown. In the longitudinal diametrical center is formed the gimlet-screw D, and the cutting-lips B are inclined inwardly, and provided 60 with cutting-spurs C in such a manner that the screw D will hold until the spurs C have severed the longitudinal fibers, and a clean cut, without the necessity of reversing the timber, and avoiding the breaking of the surrounding 65 exit, is obtained.

70 I am aware that the holding-screw and the inclined cutting-lips are not, broadly, new with me, and that the cutting-spurs have been before used, and neither of these devices is sought 75 to be covered, broadly, in this application.

75 The essential feature of the invention rests in the combination of the inwardly-inclined cutting-lips, the spurs C, and the holding-screw, as shown.

77 It will be observed that by my construction the cutting-surfaces may readily be sharpened without changing the angle of the file and without injuring the spurs.

80 What I claim as new is—
As a new article of manufacture, the auger-bit herein described, consisting of the body A, rectangular portion a, the inwardly-inclined cutting-lips B, having cutting-spurs C, and the holding-screw D, the whole formed and arranged as and for the purposes set forth.

85 In testimony whereof I affix my signature in presence of two witnesses.

WILLIAM L. PARMELEE.

Witnesses:

H. CLAY SMITH,
JNO. ROBT. EDSON.
